UNITED STATES PATENT OFFICE.

CLAUDE E. HAND, OF WALLA WALLA, WASHINGTON.

PRINTING MASK.

Application filed November 7, 1921. Serial No. 513,273.

To all whom it may concern:

Be it known that I, CLAUDE E. HAND, a citizen of the United States, residing at Walla Walla, in the county of Walla Walla and State of Washington, have invented certain new and useful Improvements in Printing Masks, of which the following is a specification.

This invention relates to printing masks 10 as applied to printing presses where two or three colored printing is desired. One object of the invention is to provide a means of the class mentioned that is cheap to manufacture, that is quickly attachable or detachable without alteration of the press. A further object of the invention is to provide a means whereby the several ink colors used with the device cannot run together.

With these and other objects in view reference is now had to the accompanying drawings in which—

Fig. 1 is a plan view of the mask with auxiliary mask in place.

Fig. 2 is a half plan view of the mask 25 with auxiliary mask removed.

Fig. 3 is a sectional view on the line 3—3 of Fig. 2.

Fig. 4 is a side elevation of auxiliary mask hinge in the closed position.

Fig. 5 is a side elevation of auxiliary mask hinge in position for removal of auxiliary mask.

Fig. 6 is a side elevation of auxiliary mask latch in closed position.

Fig. 7 is a side elevation of an inking roll 35 as used on the mask with auxiliary mask removed.

Fig. 8 is a side elevation of an inking roll 40 as used on the mask with auxiliary mask in place.

Fig. 9 is an inking diagram.

Fig. 10 is an inking diagram.

Fig. 11 is a side elevation of brace.

Fig. 12 is a rear elevation of brace.

Fig. 13 is a side elevation of printing 45 press with device applied; and

Fig. 14 is a side elevation of inking roll with vibratory roll in position thereon.

Having reference to the drawings, like 50 numerals refer to like parts throughout the several views, and the numeral 1 refers to a mask provided with a relatively large and eccentrically positioned orifice 2 and a mutilated perimeter or outer edge 3. Corruga-

tions 4 are provided in the mask to main- 60 tain it slightly above the disc 5 of the printing press 6 and may be curved concentric to the perimeter of the mask, however it is ob- 65 vious that other forms of depressions will answer the same purpose. The mask is tapered in cross section to a knife edge 7 (see Fig. 3) at its inner perimeter thus to permit the printing rollers 8 and 9 respectively to come in contact with the ink on the disc.

About the perimeter of the mask are dis- 65 posed clips 10 and 11 respectively where- 70 with to receive and maintain against lateral motion an auxiliary mask 12 provided with a tongue hinge 13 and a latch 14 which will be engaged by said clips.

The mask is rigidly attached to the bed 75 of the press by the bolt 16 and uprights 17. The above mentioned auxiliary mask may be of similar knife blade section to that of the mask and is provided with corrugations 18 positioned preferably to engage the corrugations of the mask when the auxiliary mask is attached to the mask, as shown in Fig. 1. The auxiliary mask is provided with a relatively small orifice 19 centrally 80 disposed therein, and the two diametrically opposite sides 20 and 21 respectively are cut in a straight line in a manner that the side 21 will uncover a part of the relatively large orifice 2; in other words the auxiliary mask 85 is positioned on the mask to partly cover the large orifice; by this means a blank space 22 is left between this exposed portion of the large orifice and the small orifice in the auxiliary mask and will be presently explained, 90 as will a similar blank space 23 which is also provided between the small orifice and the edge 24 of the mutilated perimeter 3.

The fountain 25 is not disturbed by the addition of the mask or the auxiliary mask, 95 but ink is preferably applied to the disc 5 through the orifices by means of a hand roller, and therefore, as proper ink distribution is essential to good printing, and as a hand roller does not give proper distribu- 100 tion, it is necessary to properly spread the ink on the ink rollers which is accomplished by means of a vibratory roller 26 which rolls in contact with the ink rollers and which is designed to move reciprocatingly 105 over the ink rollers to give greater distribution of the ink on these rollers.

It is now obvious that where two or more colors of ink are used the action of the vibratory roller would soon mix the colors 110

- on the ink rollers, resulting in anything but an artistic product. Hence to avoid the mixing of the colors the ink rollers are provided with grooves 27, 28, 29, 30 and 31.
- 5 Presuming now that the auxiliary mask is removed we have the relatively large orifice 2 exposed through which ink would be received by the ink roller 9 to be distributed as shown in the inking diagram, Fig. 10, where the shaded portion 32 represents the width of type which may be covered by ink from the large orifice, the shaded portion 33 the width of type which may be covered by ink from the mutilated portion 10 3, and the space 34 that left by the groove 27 in the roller 9. In this case the blank space 23 is reduced to the size of the space 35 so that with the groove 27 positioned to register in line with a line between the 15 orifice and the blank space the ink distribution can only obtain to the groove and one color cannot pass the groove to mix with the other color. This also applies where the auxiliary mask is used, in which 20 case, however, other grooves must be cut in the roller 8 to prevent the spreading of ink over the spaces 22 and 23 and to confine it to the covering surface as shown in the inking diagram, Fig. 9.
- 25 30 In use the device is applied to the press, the form set, the necessary colors placed on the disc, the press set in motion, when a product will be obtained having varicolor work which will be as artistic as when run through a press for each color.
- Having thus described my invention, I claim:
1. In a printing mask, the combination of a mask provided with a relatively large 40 eccentrically positioned orifice and a mutilated periphery, means attached to said mask to receive and maintain against lateral and longitudinal motion an auxiliary mask, means for rigidly attaching said mask to a printing press, said auxiliary mask attachable to said mask and provided with a centrally disposed orifice, said auxiliary

mask positioned to partly cover said relatively large orifice and provide blank spaces between said orifice and the orifice in the auxiliary mask, and inking rollers provided with grooves positioned to register in line with the line between said orifices and said blank spaces.

2. In a printing mask, the combination of a mask provided with a relatively large and eccentrically positioned orifice and a mutilated periphery, said mask provided with corrugations, means to rigidly attach said mask to a printing press, an auxiliary mask detachably mounted on said mask and provided with a relatively small and centrally disposed orifice, said auxiliary mask positioned to partly cover said relatively large orifice and provide blank spaces between said orifice and the relatively small orifice, and inking rollers provided with grooves positioned to register in line with a line between said orifices and said blank spaces.

3. In a printing mask, the combination of an annular mask, having a portion of its periphery mutilated, with a relatively large orifice in said mask, and tapered in cross section to a knife edge at the inner periphery of said mask, corrugations in said mask, means for rigidly attaching said mask to a printing press, an auxiliary mask detachably mounted on said mask and provided with a relatively small and centrally disposed orifice, and further provided with corrugations, said corrugations positioned to register with the corrugations in said mask, said auxiliary mask positioned to partly cover the large orifice in said mask and provide blank spaces between said orifice and the small orifice in said auxiliary mask, and inking rollers provided with grooves positioned to register in line with a line between said orifices and said blank spaces.

In testimony whereof I affix my signature.

CLAUDE E. HAND.
